CLAIM

I claim the ornamental design for a baking pan, as shown and described.

DESCRIPTION

FIG. 1 is a top perspective view of a baking pan showing my new design;

FIG. 2 is bottom perspective view of the baking pan of FIG. 1;

FIG. 3 is a top plan view of the baking pan of FIG. 1;

FIG. 4 is a bottom plan view of the baking pan of FIG. 1;

FIG. 5 is a front elevation view of the baking pan of FIG. 1,

the back elevation view being a mirror image thereof; and,

FIG. 6 is a left side elevation view of the baking pan of FIG. 1, the right side elevation view being a mirror image thereof.

1 Claim, 5 Drawing Sheets(56)
